UNITED STATES PATENT OFFICE.

PETER GERUM, OF VANCOUVER, WASHINGTON.

DESIGN FOR A TRICYCLE.

53,495.

Specification for Design.

Patented July 8, 1919.

Application filed January 20, 1919. Serial No. 272,211. Term of patent 7 years.

To all whom it may concern:

Be it known that I, PETER GERUM, a citizen of the United States, residing at Vancouver, in the county of Clarke and State of Washington, have invented a new, original, and ornamental Design for Tricycles, of which the following is a specification, reference being had to the accompanying drawing, forming part thereof.

Figure I is a side elevation of my tricycle; Fig. II a plan view; and Fig. III, a rear view, all showing my new design.

I claim:

The ornamental design for a tricycle as shown.

PETER GERUM.
